UNITED STATES PATENT OFFICE

100,610

DESIGN FOR A BOX FOR CRAYONS

Robert W. Weeks, New York, N. Y., assignor to Art
Crayon Company, Brooklyn, N. Y., a corporation of New York

Application August 23, 1935, Serial No. 58,256

Term of patent 14 years

To all whom it may concern:

Be it known that I, Robert W. Weeks, a citizen of the United States, residing at New York, in the county of New York and State of New York, have invented a new, original, and ornamental Design for Boxes for Crayons, of which the following is a specification, reference being had to the accompanying drawing, forming a part thereof.

Fig. 1 is a front view of a box for crayons showing my new design.

Fig. 2 is a side view thereof.

The dominant feature of my design resides in the ornamentation appearing on the front of the box.

I claim:

The ornamental design for a box for crayons substantially as shown and described.

Signed at New York, New York, this 16th day of August, 1935.

ROBERT W. WEEKS.
